COILING MECHANISM FOR SHEET MATERIAL

Carl M. Yoder, Lakewood, Ohio

Application January 7, 1936, Serial No. 57,903

13 Claims. (Cl. 242—78)

This invention relates to a machine for coiling sheet material, more particularly it relates to an improved coiling drum having relatively movable sections, whereby it may be readily collapsed and expanded to facilitate attachment of the material for winding and removal of the coiled material.

The machine herein shown for illustrative purposes is adapted for coiling sheet metal of any width within the length of the drum, but the invention is not to be limited to this particular application as other materials may be coiled on the drum.

One object of the invention is to provide an improved drum of this type that is readily controlled and actuated whereby the operations of attaching the sheet material, coiling it and removing a coil are facilitated.

Another object of the invention is to provide an improved collapsible drum having relatively few sections and a simplified moving mechanism therefor, whereby the drum may be readily collapsed or expanded.

A further object of the invention is to construct an improved drum of this type wherein provision is made, in a simplified manner, to automatically expand and contract the drum.

Other objects of the invention will be apparent to those skilled in the art to which my invention relates from the following description taken in connection with the accompanying drawings, wherein.

Fig. 1 is a plan view of a machine embodying my invention.

Fig. 2 is a side elevation.

Fig. 3 is a fragmentary longitudinal section on the line 3—3 of Fig. 4.

Figs. 4 and 5 are sections on the line 4—4 of Fig. 3, the former showing the drum sections in expanded position and the latter showing the sections in contracted or collapsed position.

Fig. 6 is a section on the line 6—6 of Fig. 3.

Figs. 7 and 8 are fragmentary enlarged sections on the lines 7—7 and 8—8, respectively of Fig. 1.

In the drawings, 1 indicates a suitable base on which is mounted a housing 2 for enclosing a driving mechanism having a suitable gear reduction and reversing means for driving a shaft 3, as hereinafter set forth, said mechanism being driven by a motor 4. The shaft 3 is mounted in suitable bearings in the housing 2 and extends rearwardly beyond the housing to provide for a brake wheel 5, which is controlled by a suitable brake mechanism 6. The shaft 3 extends beyond the front of the housing 2 to support a drum 4,

consisting of a plurality of longitudinally extending sections, which are arc-shaped in cross section, namely, a stationary section 4a, and movable sections 4b, 4b, 4c, the latter sections when expanded co-operating with each other and the section 4a to form a substantially continuous cylindrical surface on which the material A is coiled or wound (see Fig. 4). Within the drum 4, the shaft 3 consists of an inner member 3a and a sleeve member 3b, preferably secured together by a key 7 for rotation as a unitary member. At its outer end the member 3a is provided with a head 8, which is rigidly secured thereto by countersunk bolts 9. The head 8 has a diameter substantially equal to that of the drum 4 to close the outer end thereof. The sleeve member 3b is provided at longitudinally spaced points with radially extending integral lugs or projections, those designated 10 at the opposite ends of the member 3b being provided (a) with seats to which the stationary drum section 4a is rigidly secured in any desired manner as by bolts 9' and (b) with suitable bearings for the opposite ends of diametrically arranged shafts 11 the purpose of which will later be set forth. The inner face of the drum head 8 is formed with recesses 12 to receive the outer ends of the shafts 11 and to accommodate collars or nuts 13 threaded on such ends to prevent endwise movement inwardly of the shafts 11. The shafts 11, at their inner ends, extend through the adjacent bearings and are provided with pinions 14, 14a, (to be later referred to), which engage the adjacent lugs 10 to prevent endwise movement of the shafts 11 outwardly. The lugs 10 also support adjacent the opposite longitudinal edges of the stationary drum section 4a the opposite ends of a pair of rods 15, on which pairs of knuckles 16 provided on the inner sides of the drum sections 4b, 4b, are pivoted. As the lugs 10 are fixed to the shaft 3 member 3b and rotate therewith, the drum sections 4a, 4b, 4b, also rotate therewith as a unit when any rotation of the shaft takes place, so that at no time is relative rotative movement between these sections and the shaft 3 effected. As shown in Fig. 3, I provide a plurality of intermediate lugs 10' having, by preference, bearings for the shafts 11 and rods 15 and preferably seats to which the stationary drum section may be secured. Furthermore and by preference, these intermediate lugs (or certain thereof) are shaped at diametrical opposite sides to form guide ways 17, which extend in parallel relation to each other and transversely to the axis of the drum, and receive and support a pair or pairs of thrust 55

devices 18. The thrust devices 18 are connected at corresponding ends (preferably integrally) to a pair of arms 19 integral with and extending inwardly from the movable drum section 4c and accordingly slidably support the latter on the shaft for movement radially thereof; but as the lugs 10, in which the thrust members 18 are mounted, are connected to and rotate with the shaft member 3b, it will be seen that the movable drum section 4c rotates therewith at all times and that no relative rotative movement between them is effected when the section is moved outwardly or inwardly or otherwise. The movable section 4c is connected to the sections 4b, 4b, by pairs of links 20, each pivoted at its opposite ends to the adjacent sections, and so arranged that radial movement of the section 4c inwardly will effect an inward swinging movement of the sections 4b, 4b, simultaneously about the rods 15 and outward radial movement of the section 4c will swing the sections 4b, 4b, simultaneously outwardly; the parts being correlated so that when the sections 4b, 4b, 4c, are moved outwardly or expanded, they co-operate with each other and the stationary section 4a to form a continuous winding surface for the material A, as shown in Fig. 4. In this latter position of the drum sections 4b, 4b, 4c, the links 20 by preference extend at substantially right angles to the direction 30 of movement of the thrust devices 18, so that (a) in the movement of these devices inwardly (toward the left in Fig. 4) to the position shown in Fig. 5, the section 4c is moved inwardly radially and the sections 4b, 4b, are swung inwardly, whereby the drum is contracted or collapsed, and (b) in the movement of these devices in the opposite direction, the sections 4b, 4b, 4c, are expanded to the position shown in Fig. 4. Accordingly in my construction, I operate one drum 40 section inwardly and outwardly and through it I operate the other movable sections.

The links 20 are pivoted to the sections 4b, 4b, 4c, by means of rods 20' which extend longitudinally of the drum through openings formed in the walls of the sections, and held against endwise movement by cotter pins 20a, the openings for the rods carried by the section 4c being preferably at the points of connection of the thrust devices 18 and arms 19.

50 The means for rotating the shaft 3 comprises a collar 21 rotatably fitting the inner end of the shaft member 3a and drivingly connected to the driving mechanism within the housing 2 and keyed to the member 3a by keys 22, whereby the connected members 3a, 3b, are driven. As shown in Fig. 6, the key-ways 23 formed in one of these parts, preferably the collar 21, are extended in opposite directions angularly to permit of limited rotation of the collar 21 relative to the shaft 60 member 3a, so that in starting or stopping the collar 21 it rotates relative to the member 3a before it acts through the keys 22 to drive or to effect stoppage or reversal of the shaft 3. The purpose of this relative movement is to provide direct 65 operating connections between the shaft driving means and the thrust devices 18, whereby the operation of the latter is automatic and independent of the driving connection from the collar 21 to the shaft 3 for rotating the latter, although 70 both operations are effected from a single driven element.

The operating connections for moving the thrust devices 18 consist of the following: 24 indicates racks provided on the outer sides of the 75 thrust devices 18. 25 indicates pinions meshing

with the racks 24 and fixed to the shafts 11. At their inner ends the shafts 11 are provided with the gears 14, 14a, already referred to. The gear 14 meshes with the gear teeth 26 provided on the collar 21, whereas the gear 14a meshes with an 5 idler 27 which in turn meshes with the teeth 26, whereby are secured proper directional movements of the shafts 11.

The idler 27 is rotatably supported on a shaft carried by the free end of a bracket 27' bolted to 10 the innermost lug 10 on the shaft member 3b and drum section 4a (see Figs. 6 and 7).

The collar 21 is mounted in bearings 21a in the front wall 2a of the housing 2 and is preferably formed integral with a gear 21' which is connected to and driven by the driving mechanism (not shown) within the housing 2. The gear 21' is arranged between the housing wall 2a and a shoulder 3x on the shaft 3 to prevent endwise movement of the collar. 20

From the foregoing description it will be understood that when the driving mechanism is started, the collar 21 will first or initially rotate relative to the shaft 3 an angular distance determined by the width of the key-ways 23 and thereafter through the keys 22, it will become drivingly connected to the shaft 3 to rotate the drum and effect coiling of the material thereon. During this initial movement of the collar, it will cause a rotation of the shafts 11, and through 30 the gears 25 thereon and racks 24 on the thrust devices, the drum sections will be expanded. At the end of the coiling operation, the rotation of the collar is stopped, permitting the momentum of the shaft 3 and drum to rotate relative to the 35 collar 21, whereby the moving means for the thrust devices will effect a collapsing of the movable drum sections. However, if these sections do not become collapsed, the collar 21 may be rotated in the opposite direction far enough to 40 move the movable drum sections to their collapsed position.

The stationary drum section 4a is cut away along one longitudinal edge to provide a recess 28 in which is removably fixed a clamping member 45 29, the latter forming with a clamping member 29' removably and adjustably secured on the tail portion 4b' of the adjacent drum section 4b, a clamping means for the free end of the material A. As the clamping member 29' is disposed beyond the pivot for the drum section 4b, the clamping members will be separated when the said section is in its collapsed position, but movement of said section to its expanded position will move the clamping member 29' toward the 55 clamping member 29 and thus clamp or grip the material between them. By preference the clamping members are provided with related interlocking elements to insure a positive gripping of the material. By interposing one or shims 30 between the tail portion 4b' and the clamping member 29', the clamping means may be adjusted to receive and clamp materials of different 60 thicknesses.

To those skilled in the art to which my invention relates, many changes in construction and widely differing embodiments and applications of the invention will suggest themselves without departing from the spirit and scope of the invention. My disclosures and the description herein are purely illustrative and are not intended to be in any sense limiting. 65

What I claim is:

1. In a coiling device for sheet material, a support, a shaft rotatably mounted on said sup- 75

- port, a drum comprising a plurality of relatively movable sections carried by said shaft, a driven element, means operated by said element for moving certain of said sections, connections between 5 said element and said shaft for rotating the latter, and means for driving said element.
2. In a coiling device for sheet material, a support, a shaft rotatably mounted on said support, a drum carried by said shaft and comprising a plurality of sections certain of which are movable to permit collapsing of the drum, means for moving the movable sections independently of the shaft, and means arranged to be engaged by an element of said moving means for rotating 10 said shaft.
3. In a coiling device for sheet material, a support, a shaft rotatably mounted on said support, a drum carried by said shaft and comprising a plurality of sections certain of which are movable to permit collapsing of the drum, said means including an element which is movable relative to said shaft to drivingly engage therewith and which during such relative movement operates 15 said movable sections independently of said shaft.
4. In a coiling device for sheet material, a support, a shaft rotatably mounted on said support, a drum carried by said shaft and comprising a plurality of sections certain of which are movable to permit collapsing of the drum, a driven element for driving said shaft, mounted thereon for limited movement relative to said shaft when started and stopped, means operated by said element during said relative movement to operate said movable sections independently 20 of the shaft, and means for driving said element.
5. In a coiling device for sheet material, a support, a shaft rotatably mounted on said support, a drum carried by said shaft and comprising relatively movable sections, one of said sections being movable radially and the sections at the opposite sides of said radially movable section being pivoted adjacent one longitudinal edge thereof, devices at opposite sides of said shaft and connected to said radially movable section for moving it, links between said pivoted sections and said devices for moving said sections, means for rotating said shaft including driving 25 and driven elements having engaging elements arranged to permit a relative limited movement between them in starting and stopping said shaft, and operating connections between said driving element and said devices for moving the latter independently of said shaft.
6. In a coiling device for sheet material, a support, a shaft rotatably mounted on said support, a drum carried by said shaft and comprising a plurality of sections certain of which are movable to permit collapsing of the drum, a pair of thrust devices slidably mounted on opposite sides of said shaft for movement at right angles thereto and connected to one of said movable sections for moving it radially, operating 30 connections between said radially movable section and the remaining movable sections, said operating connections serving to support the last mentioned movable sections when said sections are in expanded position, means for rotating said shaft including driving and driven elements having engaging elements arranged to permit relative limited movement between them in starting and stopping said shaft, and operating connections between said driving element and said thrust devices for moving the latter independently of said shaft.
7. In a coiling device for sheet material, a support, a shaft rotatably mounted on said support, a drum carried by said shaft and comprising a plurality of sections, one of said sections being stationarily fixed to said shaft, the diametrical section being mounted on said shaft to move radially thereof and each of the remaining sections being pivotally mounted along one edge on said shaft, devices on opposite sides of said shaft and connected to said radially movable section, a link between each device and the adjacent pivoted section for moving the latter, means for rotating said shaft including driving and driven elements having engaging elements arranged to permit a relative limited movement between them 35 in starting and stopping said shaft, and operating connections between said driving element and said operating devices for moving the latter independently of said shaft.
8. In a coiling device for sheet material, a support, a shaft rotatably mounted on said support, a drum carried by said shaft and comprising a plurality of sections, one of said sections being stationarily fixed to said shaft, the diametrical section being mounted on said shaft to move 40 radially thereof and each of the remaining sections being pivotally mounted along one edge on said shaft, operating connections between each said pivoted section and said radially movable section, a separate shaft mounted in and extending longitudinally of said drum parallel to said first mentioned shaft, operating means between said separate shaft and said radially movable section for moving it, and means adjacent one end of said drum for rotating said separate shaft, 45 said rotating means being arranged to drive said first mentioned shaft after a predetermined movement of said separate shaft.
9. In a coiling device for sheet material, a support, a shaft rotatably mounted on said support, a drum carried by said shaft and comprising a plurality of sections, one of said sections being stationarily fixed to said shaft, the diametrical section being mounted on said shaft to move radially thereof and each of the remaining sections being pivotally mounted along one edge on said shaft, operating connections between each 50 said pivoted section and said radially movable section, a separate shaft mounted in and extending longitudinally of said drum parallel to said first mentioned shaft, operating means between said separate shaft and said radially movable section for moving it, and means adjacent one end of said drum for rotating said separate shaft, 55 said rotating means consisting of a collar geared to said separate shaft for rotating it independently of said shaft and arranged after a predetermined movement thereof to engage and rotate said first mentioned shaft.
10. In a coiling device for sheet material, a support, a shaft rotatably mounted on said support, a drum carried by said shaft and comprising a plurality of sections certain of which are movable to permit collapsing of the drum, and means for operating said movable sections and driving 60 said shaft, one element of said means being common to said sections and shaft and mounted to permit its limited movement relative to the latter.
11. In a coiling device for sheet material, a support, a shaft rotatably mounted on said support, a drum carried by said shaft and comprising a plurality of sections certain of which are movable to permit collapsing of the drum, a driven collar rotatably fitting said shaft and arranged to be drivingly connected thereto to 65

rotate it when rotated on said shaft a predetermined distance, and operating connections between said collar and said movable sections arranged to move the latter during movement of said collar on said shaft.

5 12. In a coiling device for sheet material, a support, a shaft rotatably mounted on said support, a drum comprising a plurality of sections one of which is fixed to said shaft, the remaining sections being relatively movable, means for moving said movable sections, and a driven element for rotating said shaft, said element being movable relative to said shaft in starting the rotation thereof and drivingly connected to said moving 10 means and arranged to operate said means prior to the rotation of said shaft.

13. In a coiling device for sheet material, a support, a shaft rotatable thereon, a drum carried by said shaft and comprising a plurality of sections, one thereof being fixed to said shaft, an- 15

other section being disposed opposite said fixed section and movable radially to and from said shaft and a section at either side of said shaft and pivoted thereto adjacent said fixed section, a pair of elements slidably mounted on opposite sides of said shaft and connected at their outer ends to and supporting said movable section on said shaft for movement radially thereof, said elements being provided with racks, shafts supported on and parallel to said first mentioned shaft within said drum sections and each provided with a pinion in engagement with one of said racks for moving the adjacent element, and connections between said first mentioned shaft and said last mentioned shafts for rotating the 15 latter, and linkage between said elements and said pivoted drum sections for moving the latter simultaneously with said radially movable section.

CARL M. YODER. 20
